UNITED STATES PATENT OFFICE.

GUSTAV KATZENSTEIN, OF BERLIN, GERMANY.

WOOL-WASHING MACHINE.

SPECIFICATION forming part of Letters Patent No. 611,432, dated September 27, 1898.

Application filed November 18, 1897. Serial No. 658,912. (No model.)

To all whom it may concern:

Be it known that I, GUSTAV KATZENSTEIN, a citizen of the Empire of Germany, residing at Berlin, Germany, have invented certain new and useful Improvements in Apparatus for Washing and Purifying Wool and Cotton Fibers and other Fibrous Material, of which the following is a specification.

This invention relates to an improved apparatus for washing and purifying wool and cotton fibers and other fibrous material; and the object of the invention is to provide an apparatus in which the purifying-solution is intimately mixed with the fibrous material and the cleaning of the fibers accomplished without the formation of knotted particles, so that the material is purified in a more thorough manner than is possible in appliances heretofore in use.

The invention consists of an apparatus for washing and cleaning fibrous material, comprising a stationary vessel provided with an arched cover of special construction and an agitator for imparting centrifugal motion to the mixture of fiber and purifying solution, and, further, of certain details of construction, which will be fully described hereinafter and finally pointed out in the claims.

In the accompanying drawings, Figure 1 represents a vertical central section of the apparatus for purifying wool and cotton fibers. Fig. 2 is a plan view of the cover and attached funnel in inverted position. Fig. 3 is a top view of the centrifugal wheel *e*, Fig. 1. Fig. 4 is a top view of the annular trough *p*, Fig. 1, and adjacent parts. Fig. 5 is a vertical central section of a modified form of construction of the apparatus. Fig. 6 is a plan view of a portion of Fig. 5, and Fig. 7 is a detail top view of the steam turbine wheel.

Similar letters and figures of reference indicate corresponding parts.

In the apparatus shown in Figs. 1 to 4 a vessel *b*, made of circular or parabolic shape, is supported on a curved standard *a* and is closed at its upper part, as shown in Fig. 1, by means of an annular arched cover *c*, which is attached to the circumference of the vessel *b* and which is formed with a central inwardly-extending spout *f*. In bearings of the standard *a* is arranged a hollow rotary shaft *d*, to the upper end of which, inside the ves-

sel *b*, is keyed a centrifugal wheel *e*, which is shown in section in Fig. 1 and in plan view in Fig. 3.

To the mouth of the internal spout *f* of the cover *c* is attached a funnel *g*, the discharge-tube of which extends into the mouth of the centrifugal wheel *e* and supports at its interior a hollow distributing-cone *i*, which communicates by tubes *k*, attached to the tube *h*, with the interior of the vessel *b*. This distributing-cone serves, furthermore, as a cover for the upper end of the hollow shaft *d*.

A tube *l*, forming a continuation of the hollow shaft *d*, connects the lower end of the hollow cone with the same.

Around the funnel *g* is arranged a wire net *m*, so that no part of the product can pass into the pipe *k*. At the lower part of the hollow shaft *d* are arranged a number of small discharge-nozzles *r*, below which an annular trough *p* is arranged concentrically to the hollow shaft *d*, as shown in Figs. 1 and 4. The interior of the cover *c* is provided with radial or spiral guide-vanes *s*, as shown in Figs. 1 and 2. The vessel *b* is provided with guide vanes or blades *w*, which form a continuation in downward direction of the curved vanes *s*.

The operation of this apparatus is as follows: The centrifugal wheel *e* is set into quick rotary motion by means of any suitable power transmission *z*, and water is conducted at the same time through the supply-pipe *y* into the funnel *g*, while the fibrous material is introduced at *f* and is conducted to the wheel *e* through the funnel *g*. The centrifugal wheel *e* throws the fibrous material, which is conducted to the same in the direction of arrows *n*, owing to the *vis viva* imparted to the material along the vanes or ribs *w s*, so that it is returned along the tubular central portion *f* of the cover into the funnel *g*. In this manner a continuous rapid circulation of the water and fibrous material takes place, whereby a reliable and quick cleaning of the fibers is produced, so that the latter remain always in a loose flaky condition without forming knotted particles. The separated impurities, which are usually specifically lighter than water, are collected near the net *m* and are drawn, with the water, through the net *m*, the pipe *k*, through the hollow distributing-

cone *i*, the hollow shaft *d*, and small nozzles *r* into the trough *p*. From the latter the water is conducted off through the pipe *o*. For the purpose of sterilizing the fibrous material steam can be conducted through the pipe *x* into the vessel *b*.

In the construction shown in Figs. 5 to 7 the vessel *b'* is made of conical shape, while the cover *c'* is provided with guide vanes or 10 ribs *s'* in the same manner as in the apparatus shown in Fig. 1. At the center of the vessel is likewise arranged a hollow shaft *d'*, which turns in step and neck bearings 8 and 9. The shaft *d'* is provided with stirrer-arms 10, and 15 carries at its lower end a so-called "Segner" turbine wheel 11, which is shown in detail plan view in Fig. 7. The upper end of the hollow shaft is connected with a steam-supply pipe 12. The upper part 13 of the vessel *b'* is enlarged 20 and provided with an annular chamber 14, which serves for conducting off the muddy water. A sieve is attached to the vessel at the opening into the annular chamber 14, which prevents the passage of the fibers, but 25 through which the purifying solution and impurities pass to the outlet-pipe. The vessel *b'* can be drained through a pipe 15, which is connected to the bottom of the same. The operation of this apparatus is almost exactly 30 the same as that shown in Fig. 1. The water used for cleaning the fibrous material is admitted at *f* into the interior of the vessel. The turbine wheel 11 is set in quick rotation by the steam emitted through the same, so 35 that the stirrer-arms 10 are quickly rotated in the vessel *b'*. The steam produces simultaneously the sterilization of the fibrous material and an intense motion of the solution. By the conical shape of the vessel *b'* is pro- 40 duced the gradual rising of the water with the fibrous material, so that the mixture passes by the *vis viva* imparted to it in the

direction of the arrows *n* along the vanes or ribs *s'* back to the center of the vessel, where it is taken up again by the stirrer-blades 10, 45 so as to be moved in outward direction, and so on, it being kept in continuous agitation and circulation. The motion of the centrifugal wheel *e* or turbine wheel 11 can also be accomplished in any other preferred manner. 50

For removing the fibrous material from the apparatus the cover is removed, together with the funnel *g*, or tilted, while in Fig. 5 the cover is simply lifted off. If this is not desired, the fibers may instead be drawn off 55 through a suitable pipe at the bottom of the vessel.

Having thus described my invention, I claim as new and desire to secure by Letters Patent—

1. An apparatus for washing and cleaning fibrous material, which consists of a stationary vessel provided with an arched cover, a rotary agitator for imparting centrifugal motion to the washing liquid, and radial vanes or ribs at the under side of the cover for returning the solution back toward the center of the vessel, substantially as set forth. 60

2. An apparatus for washing and cleaning fibrous material, consisting of a stationary vessel, an arched cover having a central downwardly-extending spout, radial vanes at the under side of the cover, a rotary motor for imparting centrifugal motion to the washing liquid, means for agitating the solution, and 70 means for drawing off the washing-water, substantially as set forth. 75

In testimony that I claim the foregoing as my invention I have signed my name in presence of two subscribing witnesses.

GUSTAV KATZENSTEIN.
